STEPHEN DE ORLOW, OF LANSING, MICHIGAN, ASSIGNOR TO DE ORLOW PRODUCTS CORPORATION, OF LANSING, MICHIGAN, A CORPORATION OF MICHIGAN

SKATE

Application filed January 13, 1930. Serial No. 420,463.

The present invention pertains to a novel skate intended primarily for ice skating although the novel features thereof may also be embodied in a roller skate.

The principal object of the invention is to provide a skate of the type having sole and heel plates permanently attached to a skating shoe, but in the present instance the blades or runners of the skates are detachable with respect to the sole and heel plates, so that the user may wear the shoes in a vehicle or may even walk a short distance to the skating rink, thereby avoiding the necessity of wearing walking shoes and carrying the skating shoes.

The invention embodies a novel and simple means for attaching the runner to the sole and heel plates, and the attachment is secured by nuts associated with the runner and adapted to bind against the plates. The nuts may be securely tightened and subsequently released when necessary by the use of a small stamped metal socket wrench of pocket size.

Another object of the invention is to provide auxiliary means for resisting the normal rearward thrust of the runner member during its forward movement over the ice. This means consists of a rearwardly facing shoulder at the forward end of the runner and adapted to abut a portion of the sole plate when the runner is attached to the plates. It will be obvious that the portion of the sole plate engaged by the shoulder presents an obstruction to rearward slippage of the runner.

The invention is fully disclosed by way of example in the following description and in the accompanying drawings, in which—

Figure 1 is a plan view of the skate;

Fig. 2 is a side elevation, showing the sole and heel plates and binding nuts in section;

Fig. 3 is a detailed section of the heel plate with an attaching stud inserted therein prior to attachment; and

Fig. 4 is a plan view of the heel plate.

Reference to these views will now be made by use of like characters which are employed to designate corresponding parts throughout.

As already indicated, the skate comprises sole and heel plates adapted for permanent attachment to the sole and heel respectively of a skating shoe 1. The sole plate 2 is a stamped metal member of appropriate shape and has a rim portion 3 of such surface curvature as to make surface contact with the sole 4 of the shoe. The plate has countersunk apertures 5 to receive screws 6 which fix the plate to the sole as shown in Figure 2.

Within the marginal portion 3, the plate is depressed as at 7 except for an area 8 engaging the sole and further excepting a circular portion 9 which is depressed to a less extent than the portion 7. In the portion 9 is formed an aperture consisting of a substantially semi-circular portion 10 at the forward end and having straight lateral walls 11 which converge slightly to a straight rear wall 12 lying transversely of the plate.

To the heel 13 of the shoe is secured a suitably shaped heel plate 14 having an upstanding marginal rim 15 which engages the heel. The body of the plate is formed with a circular depression 16 similar to the depression 9 previously described, and around the depression 16 is a deeper depression 17 immediately within the rim 15. The depression 17 has countersunk apertures 18 to receive screws 19 which fix the plate to the heel. The depression 16 is formed with an aperture similar to that in the sole plate and comprising parts 10', 11' and 12' corresponding to the parts 10, 11 and 12 of the previously described aperture.

The runner or blade 20 has a pair of studs 21 threaded at 22 and having blank upper extremities 23 receivable in the forward or semi-circular ends of the slots in the sole and heel plates. The blank ends 23 are slotted radially, or diametrically at 24, whereby the studs may be moved into the narrower ends of the apertures to bring the straight walls 12 and 12' of the apertures into engagement with the rear walls of the slots as illustrated in Figure 2.

On the threaded portions of the studs are mounted nuts 25 with flat tops 26 adapted for surface contact with the depressed portions 9 and 16. In fastening the skate

to the plates, the nuts are moved downwardly on the studs as shown in Figure 3, and the studs are inserted in the apertures in the manner already described to take the 5 position shown in Figure 2. The nuts are then tightened against the depressed portions 9 and 16 as illustrated in the sole plate 8 in Figure 1. The shanks of the nuts may be of polygonal cross section and engageable 10 by a small stamped metal socket wrench which may conveniently be carried in the pocket of the user.

It will be seen in Figures 1 and 2 that the forward tip of the sole plate 8 is longitudinally slotted at 27 for a short distance into the depression 7. The forward end of the runner 20 is notched to form a rearwardly facing shoulder 28, and the relation of parts is such that this shoulder engages the rear 20 end of the slot when the skate is assembled as shown in Figure 2. The rear wall of the slot thus provides an abutment for the shoulder 28 and thus takes the rearward thrust of the skate during the forward movement of the latter over the ice and prevents rearward slippage of the skate.

Although a specific embodiment of the invention has been illustrated and described, it will be apparent that various alterations in the details of construction may be made without departing from the scope of the invention, as indicated by the appended claims.

What I claim is:—

1. A skate comprising sole and heel plates, 35 a runner, threaded studs extending from said runner and adapted for interlocking directly with said plates, and nuts on said threaded studs adapted to bind against said plates.

2. A skate comprising apertured sole and heel plates, a runner, threaded studs extending from said runner and adapted for interlocking directly with said plates at the apertures thereof, and nuts on said threaded 45 studs adapted to bind against said plates.

3. A skate comprising apertured sole and heel plates, a runner, threaded studs extending therefrom and having radially slotted ends adapted for reception in the apertures of said plates, said slots being adapted 50 to receive portions of said plates at the edges of said apertures, and nuts on said threaded studs adapted to bind against said plates.

4. A skate comprising sole and heel plates having each a depression and an aperture formed in the depressed portion, a runner, threaded studs extending therefrom and having radially slotted ends adapted for reception in the apertures of said plates, said 55 slots being adapted to receive portions of said plates at the edges of said apertures, and nuts on said threaded studs adapted to bind against said plates.

5. A skate comprising sole and heel plates 60 having each a depression and an aperture

formed in the depressed portion, each of said apertures terminating in a straight wall lying transversely of the respective plate, a runner, threaded studs extending therefrom and having slotted ends adapted for reception in the apertures and adapted to receive portions of said plates at the straight 70 walls of said apertures, each of the slots in said ends having a straight wall in the stud adapted to engage the straight wall of the 75 corresponding aperture, and nuts on said threaded studs adapted to bind against said plates.

6. A skate comprising sole and heel plates, 80 a runner, means for detachably securing said runner to said plates, said sole plate having a depressed portion stamped out of the general plane thereof, and a rearwardly facing shoulder formed at the forward end of said runner and adapted to engage said depressed 85 portion, whereby to resist rearward thrust of said runner.

7. A skate comprising sole and heel plates, 90 a runner, means for detachably securing said runner to said plates, the forward tip of 95 said sole plate having a depressed portion stamped out of the general plane thereof and a shoulder formed at the forward end of said runner and adapted to engage said depressed portion, whereby to resist rearward thrust of said runner.

8. A skate comprising sole and heel plates, 100 a runner, means for detachably securing said runner to said plates, the forward tip of said sole plate being depressed, and slotted longitudinally partially through said depressed portion, the forward end of said runner being receivable in the slot and having a shoulder adapted to engage said depressed portion at the rear end of the slot, whereby to resist rearward thrust of said runner. 105

In testimony whereof I affix my signature.
STEPHEN DE ORLOW.
